FOLDING TABLE WITH SECTIONAL TOP

Michael J. Misko, Inglewood, Calif.

Application January 25, 1946, Serial No. 643,393

6 Claims. (Cl. 311—89)

1

This invention relates generally to the class of furniture and pertains particularly to an improved folding table structure.

A primary object of the present invention is to provide a table of a rectangular form which is divided into sections which are adapted to be folded one over the other so as to reduce the table to a small compact unit whereby it may be conveniently transported or stored away.

Another object of the invention is to provide a table of the type commonly employed for playing cards, which is divided into four parts along perpendicular lines and wherein the four parts are so joined together that they may be readily folded up to lie one upon the other so that the completed table structure will be reduced to approximately one-fourth of the original size, facilitating its ready packing into a motor vehicle or storage space, or its convenient transportation from one place to another.

Still another object of the invention is to provide in a folding table structure of the character stated, a novel hinge unit for facilitating the separation of two portions of the table top and the folding of such portions together one over the other.

The invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in perspective of a table constructed in accordance with the present invention and set up for use;

Figure 2 is a view in top plan and on an enlarged scale, of the table top, a portion of the same being broken away to show the hinge coupling between two sections and the legs being shown in dotted outline beneath the top;

Figure 3 is a view illustrating two halves of the table drawn apart upon the coupling hinge and with one of the quarter portions of each half folded into position against the other quarter portions, preparatory to folding the two half sections over one upon the other to the position shown in dotted outline;

Figure 4 is a side view of the coupling hinge bar;

2

Figure 5 is a section view taken substantially on line 5—5 of Figure 2;

Figure 6 is a view in top plan of the coupling hinge bar;

Figure 7 is an enlarged view showing a portion of the hinge bar in association with the pivoted locking member;

Figure 8 is a detailed longitudinal section of one of the extensible legs;

Figure 9 is a sectional view taken substantially on the line 9—9 of Figure 2 between the two halves with a portion of one flange broken away.

Referring now more particularly to the drawings the numeral 10 usually designates the top of the table structure of the present invention, which table structure is of square outline and of the type commonly employed for playing cards.

In accordance with the invention the table top is divided into four quarter sections which are designated A, B, C and D and the sections A and B are connected together by a hinge 11 while the sections C and D are connected together by a hinge 12. While any suitable type of hinge connection may be used between the sections, one of the type known as a piano hinge is preferred and is illustrated in Figure 3. Thus it will be seen that while the table top as a whole is made up of four sections, it is actually divided into two separable portions which are designated 13 and 14, the portion 13 being made up of the two quarters A and B and the portion 14 being made up of the two quarters C and D.

The opposing sides of the two portions 13 and 14 are bordered upon the under side of the top panel 15 by the flanges 16 and the outer sides of the sections have upon the under sides of the panels, the outside encircling flanges 17 which, when the top is set up for use as shown in Figure 1, make the usual complete bordering flange for the table top.

In the angle formed at each corner of the top by the bordering flanges 17, a suitable hinge bracket 18 is secured, between one portion of which and the inner side of a bordering flange 17 is pivotally mounted the upper end of a two part telescoping leg 19.

Each of the telescoping legs comprises the upper section 20 and the lower section 21 and as shown in Figure 8, the upper section is provided with the bore or passage 22 which opens through its lower end and into which is slidably received one end of the lower section 21 of the leg. Section 21 of the leg has formed therein a series of notches 23 in which may be selectively engaged the locking pin 24 which is carried by a spring

leaf 25 upon the upper leg section and extends through a suitable aperture for engagement in one of the notches 23 as shown in Figure 8. Thus it will be seen that when the legs 19 are shortened to the desired extent each one may be folded into position against the under side of the top panel of the quarter section to which it is hingedly attached and consequently these sections may be folded one against the other by means of the hinge connections 11 and 12, as shown in Figure 3 and the legs will be housed between them. When it is desired to use the table the legs can be extended after being swung down to a position perpendicular with the table top, merely by pulling outwardly upon the portions 21 thereof until the desired length is obtained.

The opposing flanges 16 of the sections A and C have formed therethrough coinciding openings 26 and secured to the under sides of the adjacent panels 15 and at opposite sides of the openings 26, are the spaced parallel guide bars 27, each of which abuts at one end against the inner side of a flange 16 and each of which has formed in its inner edge a guide slot 28. The bars 27 of one section are in alignment with the corresponding bars of the adjacent section and they receive between them the three part coupling hinge generally designated 29, and which comprises the central section 30 and the end section 31 which are hingedly joined to the central section by the hinge members 32 so that the sections may be disposed in end aligned relation or may be folded inwardly onto or toward the center section as desired. This hinge bar extends transversely of the space between the opposing flanges 16, through the aligned openings 26 so that one end section 31 and a portion of the central section 30 lies between the two guide bars 27 under one table top section and the other hinge bar end portion 31 and a part of the central portion 30 lies between the guide bars 27 of the adjacent top section.

Each of the hinge bar parts 31 carries in its opposite edges, the movement limiting pins 33. These pins slidably engage in the slots or channels 28 of the adjacent guide bars 27 and they are limited in their movement outwardly in the channels by the flanges 16 as illustrated in the Figures 2 and 9.

One of the guide bars 27 of each pair carried by a table top section A and C, has pivotally mounted in a recess 34, Figure 7, an eccentric locking wedge 35. The eccentric wedge is mounted upon the pivot 36 and it has an arm 37 by means of which it may be oscillated to extend the tapered or wedge portion 35' inwardly where it will be forced beneath the adjacent portion 31 of the hinge bar and the guide as shown in Figure 5. Thus the hinge part 31 will be wedged tightly against movement and the adjacent quarter section of the table top will be locked to the hinge bar. When it is desired to shift the top section the arm 37 is oscillated in the proper direction to withdraw the wedge locking edge 35' and the table top portion may then be drawn outwardly on the locking end away from the other portion and when the locking members of both portions are released it will be seen that such portions 13 and 14 can be readily separated so as to move the hinged ends of the hinge bar away from their respective top portions to the extent illustrated in Figure 3.

The quarter sections B and D may be suitably coupled together so as to establish a rigid connection between them when the table top is set

up for use, by the provision of aligned pairs of guide bars 38 upon the under sides of the top panels 15, corresponding to the guide bars 27 and slidably mounted between these guide bars 38 to extend across the joint or space between the quarter sections B and D is a single piece rigid coupling bar 39. The spaced guides 38 upon one of the quarter sections is of sufficient length to receive the entire coupling bar 39, thus allowing the quarter sections to be independently swung into position against the parts A and C to which they are respectively coupled by the hinges 11 and 12. After the two table portions 13 and 14 have been separated and quarter sections B and D have been swung to position beneath the adjacent respective sections A and C so that the structure appears as it is shown in full lines in Figure 3, one of the portions may then be swung on the double hinge bar 29 into the dotted outline position shown in Figure 3 to produce the completely folded table structure.

From the foregoing it will be readily apparent that there has been provided in the present invention, a novel table structure which can be readily folded into a small compact unit for storage, transportation or other easy handling and which may be easily and quickly unfolded and set up for use to provide a rigid and safe table for any desired use.

30 I claim:

1. A folding table comprising a top divided along two right angularly related lines to form four sections, hinge means disposed on one of said lines and coupling the sections together in pairs to form the top in two portions, the sections of one portion being foldable against the sections of the other portion along one of said lines, a pair of opposed guides carried by adjacent sections of the two portions and aligned transversely of the other one of the two division lines, a hinge bar slidably supported between the said guides and across the division between the two portions and comprising a long center part and end parts each hingedly connected to an end of the center part, a sliding coupling between opposite longitudinal edges of each end part of the hinge bar and a pair of guides of one section whereby the center part of the hinge bar may be disposed in a position between the two table portions upon separation of one portion from the other, means for locking the end parts of the hinge bar to the guides when the two table portions are moved together on the hinge bar, means for establishing a rigid connection between the other two sections of the two table portions when the portions and sections are in a common plane, and a leg carried by each of said sections.

2. A folding table of the character stated in claim 1, wherein said guides are in the form of spaced parallel strips secured to the underside of the table top and having longitudinal slots in their opposed faces, and the said sliding coupling between the opposite longitudinal edges of the end parts of the hinge and a pair of guides constituting pin members carried by said longitudinal edges and slidably engaging in said slots.

3. A folding table of the character stated in claim 1, in which the said means for locking the end parts of the hinge bar to the guides, comprises an eccentrically pivoted plate supported upon a guide of each pair and adapted when oscillated in one direction to move into wedging engagement with a longitudinal edge of an adjacent end part of the hinge bar.

4. A folding table of the character stated in

claim 1, wherein each pair of guides comprises relatively long spaced parallel strips secured to the underside of a top section, said strips having slots formed longitudinally in the opposed inner faces thereof, the said parts of the hinge bar being flat and interposed between the grooved edges of the guide strips and adapted to lie in a common plane against the underside of the table top when the portions of the table top are in a common plane, the sliding coupling between each end part of the hinge bar and a pair of guides comprising pins carried in the opposite longitudinal edges of the end parts and slidably engaged in said slots.

5. A folding table of the character stated in claim 1, wherein each pair of guides comprises relatively long spaced parallel strips secured to the underside of a top section, said strips having slots formed longitudinally in the opposed inner faces thereof, the said parts of the hinge bar being flat and interposed between the grooved edges of the guide strips and adapted to lie in a common plane against the underside of the table top when the portions of the table top are in a common plane, the sliding coupling between each end part of the hinge bar and a pair of guides comprising pins carried in the opposite longitudinal edges of the end parts and slidably engaged in said slots, the said slots of the two pairs of guides opening through the ends of the guides which are adjacent to the ends of the opposite pair, flanges extending along the adjacent edges of the top sections and each having an opening through which the hinge bar extends, the flanges extending across and closing the open ends of the slots of the guides.

6. A folding table of the character stated in

claim 1, wherein each pair of guides comprises relatively long spaced parallel strips secured to the underside of a top section, said strips having slots formed longitudinally in the opposed inner faces thereof, the said parts of the hinge bar being flat and interposed between the grooved edges of the guide strips and adapted to lie in a common plane against the underside of the table top when the portions of the table top are in a common plane, the sliding coupling between each end part of the hinge bar and a pair of guides comprising pins carried in the opposite longitudinal edges of the end parts and slidably engaged in said slots, and said means for locking the end parts of the hinge bar to the guides comprising a plate member having a tapered rounded edge and eccentrically pivotally mounted upon a guide of each pair and adapted when oscillated in one direction to have said tapered edge projected inwardly toward and in binding engagement with the adjacent end part of the hinge bar to lock the latter against movement.
